UNITED STATES PATENT OFFICE

ADOLPH M. HOLSTEIN, OF SYRACUSE, NEW YORK

KNOB CONSTRUCTION

Application filed October 8, 1928. Serial No. 311,024.

This invention has for its object a particularly simple and efficient construction of handles or knobs such as are used on radio sets to operate the dials, which is extremely simple and which greatly facilitates the quantity production of a high grade article at a low cost and eliminates drilling, tapping and broaching operations heretofore used in producing these articles and set screws used to attach them to their shanks.

The invention consists in the novel features and in the combinations and constructions and method hereinafter set forth and claimed.

In describing this invention, reference is had to the accompanying drawings in which like characters designate corresponding parts in all the views.

Figure 1 is an enlarged side elevation, partly broken away, of a knob embodying my invention.

Figures 2 and 3 are opposite end elevations thereof.

Figure 4 is an end elevation of the detached socket member.

Figure 5 is a plan view of the detached key member.

Figures 6 and 7 are respectively a fragmentary elevation and end view of the shank.

These articles as knobs have a wood body or a body made of wood fiber or any other non-metallic material, a metallic socket member embedded in the body or snugly fitted in a central opening in the body, this member being provided with a transverse key, that is, a key extending diametrically thereof and a shank having an end formed to fit the socket member and provided with a transverse open ended slot for receiving the key.

1 designates a body in the form of an ornamental knob usually formed of wood or molded wood fiber and also formed with an axial passage 2 therethrough.

3 is a socket member in the form of a sleeve snugly fitting in the passage 2 and also usually having means as a non-circular head 4 embedded in the body of the knob. As here shown, the head is formed at one end of the sleeve and is hexagonal in shape. The sleeve is bifurcated at its end remote from the head 4 and is so bifurcated by sawing or

otherwise forming a diametrically extending slot 6.

The transverse key consists merely of a short flat strip 7 with its ends in the slot 6, preferably the end edges project beyond the periphery of the sleeve.

8 designates the shank which is usually a rod, this shank being formed with a transverse open ended slot 9 in one end, the slot 9 receiving the key 7.

The method of forming the knobs consists in forcing the sleeve or socket member with the key therein into the central opening 2 of the knob 1 and pressing the hexagonal head of the sleeve into the body around one end of the opening. The sleeve is of such length that the edge at the slotted end comes flush with one end surface of the knob or body.

After the sleeve is assembled in the body, the end of the body on which the hexagonal head is exposed, is preferably covered by an ornamental button or disk 10.

The socket members are formed from hexagonal bar stock in an automatic screw machine which turns the bar round with the exception of the hexagonal heads, cuts off the socket members from the bar, bores the bottoms out of the socket members and slots the same.

The keys are sheared off at the proper length from a flat strip of steel.

The spindles or shanks are made in an automatic machine from round rods, cutting off the spindles at the proper length marking off the ends and slotting.

This construction lends itself to simplicity, efficiency and fast quantity production at a low cost and eliminates the drilling of the hole radially through the knob and the sleeve and tapping the hole to receive the set screw and also eliminates the use of a set screw. It also eliminates expensive dies and casting operations to form a cast socket member which is fitted and screwed in the passage of the knob. Heretofore, in some form of knobs, instead of using a set screw, internal lengthwise slots are broached into the wall of the bore of the sleeve for receiving the sides of a wire loop hinged to the end of the spindle or shank, the hinging requiring the

forming of a transverse hole or bore in the shank to receive inwardly bent ends or pivots of the wire loop.

By my invention, the expensive broaching operation and the expensive operation of attaching the loop to the shank are eliminated.

What I claim is:

The combination of a non-metallic body formed with a passage, a metal sleeve fitting 10 in the passage and formed with a transverse slot at one end, a transverse key in the slot and a shank having one end fitting the bore of the sleeve and formed with a transverse slot for receiving the key, the key normally 15 extending slightly beyond the periphery of the sleeve into the body.

In testimony whereof, I have hereunto signed my name, at Syracuse, in the county of Onondaga, and in the State of New York, 20 this 5th day of October, 1928.

ADOLPH M. HOLSTEIN.
